UNITED STATES PATENT OFFICE.

ROBERT J. WATERWORTH, OF SIDNEY, OHIO, ASSIGNOR TO L. M. STUDEVANT, OF SIDNEY, OHIO.

PAPER-FEEDING MACHINE.

Application filed October 3, 1925. Serial No. 60,327.

My invention relates to a paper feeding machine.

It is the object of my invention to provide a paper feeding machine having means to automatically buckle a top paper sheet by moving it in a reverse direction to the direction of ejection, flutter the sheet and eject it, at the same time automatically elevating additional sheets as desired to maintain the sheets at a predetermined point of elevation.

It is a further object to provide an ejecting mechanism as a self-contained air valve and also a controlling member in part for the buckling mechanism, the ejector and the buckling mechanism being operated from the same shaft.

It is an object of my invention to provide a single pump which may be used both to create the vacuum and the air pressure for fluttering the sheets. It is my object to include in the ejecting mechanism a relief valve for the ejector. It will thus make one self-contained unit in the ejector proper.

25 Referring to the drawings:—

Figure 1 is a side elevation of the complete machine;

Figure 2 is an end elevation of the complete machine;

30 Figure 3 is a plan view of the complete machine;

Figure 4 is a section on the line 4—4 of Figure 3;

Figure 5 is a section on the line 5—5 of 35 Figure 3 showing in detail the ejector mechanism and buckling mechanism;

Figure 6 is a detail view partially broken away and in section of the buckling mechanism;

40 Figure 7 is an end elevation of the ratchet mechanism and means of connecting the ratchet mechanism to the automatic elevating mechanism.

Referring to the drawings in detail, 1 is 45 a base upon which is mounted a driving motor 2 which drives a pump 3 through a belt 4. This pump is provided with a vacuum line on one side designated 5 and on the other side with a pair of pressure lines 6 and 7. The exact details of this pump are 50 of no importance provided that the usual vacuum can be created on one side and pressure on the other through the expulsion of air.

55 The machine is composed of side frame

members 8 which serve to support the mechanism hereinafter described. These side frame members are tied together by transverse cross bolts 9 and 10 which also serve as supports to the lugs 11 for the paper guides 12 which determine the marginal position of the paper. The paper sheets are stacked as at 13 on a platform 14 which is supported on either side by jack screws 15 working in collars 16 in the platform. The lower ends of these screws are based in the supporting collars 17 beneath which, attached to the screws, are found the beveled gears 18 which mesh with the beveled gears 19 on the operating shaft 20.

The size of the sheets to be mounted on this platform is to be determined by the maximum size of the machine and the maximum size of the platform. A single machine will have a wide range of dimensions 75 as indicated from the drawings in this application. The rotation of the jack screws will serve to elevate the stack of paper sheets. The supporting table 14 has shoulders 21 on either side which are inserted through the guideways 22 on either side carried by the frame members to cooperate in guiding this platform up and down with its load of paper.

The top of the paper sheets receives at 85 the rear edge a finger 23 which is mounted on a shaft 24 through a collar 25 and set screw 26. Another finger of greater dimension in length designated 27 is also carried by this collar so that fingers of varying length may be used in connection with sheets of varying dimensions. The shaft 24 at its outside end is carried in a collar 28 which is fixed by a set screw 29 on a sliding rod 30 carried in the bracket 31 on the upper side 95 of the machine. This rod also carries another collar 32 which in turn supports a rod 33 and a weight 34. The position of the weight on the rod 33 may be varied by the setting of the set screw 35. Suspended from this rod 30 is a lever 36 attached by the collar 37 to the rod 30. The lower end of this lever is pivoted at 38 to a lever 39. This lever 39 is pivoted at 40 on the side of the frame of the machine. Its lower end carries a spring finger 41 which is adapted to press down upon a pawl 42 which is weighted at one end and is pivoted in the middle at 43 on the lever 43. Thus when the lever 24 drops down due to the ejection 110

of sheets and it is desired to elevate the platform to put the top sheets in ejecting position, the rod 30 is rotated on its axis and the levers 36 and 39 are operated so that 5 the spring finger 41 shifts from the rear end of the weighted pawl allowing it to engage with the ratchet wheel 44 which is mounted on the shaft 21, thus rotating that shaft and elevating the platform. The forward end of the pawl is weighted to cause 10 the engagement with the ratchet. The lever 43^a is pivoted to the link 45 which in turn, at its other end, is eccentrically mounted at 15 46 on the driving wheel 47 which is driven by the main driving shaft 48 which receives its power through the belt 49. This belt is mounted on the pulley wheel 50 on the other end of the shaft 48.

Turning to the ejecting means proper, it 20 will be noted that the vacuum line 5 leads to a distributor head 51 which has a right-angled aperture or passageway 52 therein. This distributor head is carried in one arm 53 of an inverted U-shaped frame, the other arm of which is designated 54 and the head of which 55 is mounted by the set screws 56 on the transverse supporting rod 57 carried in the side brackets 58 of the frame.

This distributor head is supported by a 25 tubular shoulder 59 projecting into the arm 53. Within this shoulder passing through a plate 60 is a set screw 61 which engages with the end of the helical spring 62 in an aperture 63 within the distributor head. 30 The screw fits freely within this tubular member 59 so that the distributor is spring-pressed against the ejector 64 in order that the ports of the ejector may register with the port of the distributor head. The plate 60 is supported by the set screw 65 which is 35 threaded in the arm 53.

The ejector disc 64 is mounted on the shaft 48 and turns therewith. This ejector disc has a plurality of ports 66 which are 40 located at an angle to its major axis and are adapted to register with the port of the passageway 52 of the distributor head. These ports have right hand exit openings or ports 67 so that the paper can be sucked up against 45 the periphery of the ejector disc when the ports 66 and 52 coincide.

But in the illustration shown in Figure 5 the construction is such that there is a side port 68 instead of the port 67 which is 50 adapted to register with the port or passageway 69 in the buckling disc 70. This buckling disc has a central aperture 71 so that it will fit upon the stud shaft 72. This stud shaft is mounted on a disc 73 which engages 55 with the inside of the arm 54 and engages with the set screws 74 carried in that arm which serve to press this disc and the buckling disc against the ejector disc. The other end of the stud shaft 72 is journaled in the 60 arm 54. Carried on this disc 73 is a gear

75 which is bolted to the buckling disc by the screw 76. This gear 75 meshes with the gear 77 mounted by the set screw 78 on the shaft 48.

Returning to the ejector disc 64, it will be 70 noted that it is provided with a long, partially circular groove 79 which takes the place of an exhaust valve so that the pull upon the pump will not be so great that the pump will be stalled due to the fact that it 75 has no access to the outside atmosphere, which is provided by this groove 79 when the ejector disc is not functioning.

It will be noted that the several discs project through an opening 80 in a guide plate 80 81 against which the paper is drawn on its under side during the buckling and ejecting operations.

In order that the sheets may be fluttered 85 the pipes 7 and 6, which are the exhaust pipes from the pump, direct the exhaust air through nozzles 82 which are placed at the angle desired by means of the collars 83 and set screws 84. These collars are mounted 90 on the shaft 9.

Method of operation.

In operation, when the pump is functioning, the air is evacuated through the distributor head 52 which, when the parts are 95 in the position shown in Figure 5, serves to draw the sheet on top of the pile upwardly and move it backwardly, as that is the direction of movement of the disc 70 against the stop finger 23 and stop plate 85. As soon 100 as the buckling has been effected the disc 70 has passed by the disc 64 which is traveling in the opposite direction so that the ports 69 and 68 do not register but the ports 68 and 52 register with the port 67 in the periphery of the ejector disc 64 which, due to 105 the vacuum in the line, picks up the sheet and moves it in the reverse direction out of the feeding machine into an adjacent machine such as a folder. In the meanwhile, 110 the exhaust has been fluttering the sheets to facilitate their being picked up by the buckler and ejector. When the ejection is complete the exhaust groove 79 comes beneath the port 52, rendering the ejecting 115 mechanism inoperative until a new sheet is engaged through a new cycle of operations.

The elevating mechanism has already been described, so that as soon as the sheets get down below a predetermined point, it will 120 be brought into play and the sheets elevated again to the point desired, at which point the lifting of the rod 25 by the elevated sheets will throw the elevating mechanism out of operation.

Thus this machine automatically elevates the sheets, flutters them, buckles them by a reverse movement and ejects them out of the machine, using the ejecting mechanism also as an exhaust valve to prevent stalling of 125 130

the pump when the ejector is not ejecting the sheets.

It will be understood that I desire to comprehend within my invention such modifications as may be necessary to adapt it to varying conditions and uses.

Having thus fully described my invention, what I claim as new and desire to secure by Letters Patent, is:

- 10 1. In a feeder, means to support sheets, and an ejecting means adapted to move the paper forward consisting of a disc having a plurality of apertures passing from the side of the disc to the face of the disc and a groove in the side of the disc, and an aperture passing through the disc from one side to the other, and a distributor head connected to a vacuum pump adapted to create a vacuum in said apertures and groove 15 and means to intermittently connect the vacuum pump to the paper through said apertures and to move the paper thereby in the opposite direction.
- 20 2. In a feeder, means to support sheets, and an ejecting means consisting of a disc adapted to be rotated in one direction and having a plurality of apertures passing from the side of the disc to the face of the disc and a groove in the side of the disc, an aperture passing through the disc from one side to the other, a distributor head having a port connected to a vacuum pump adapted to create a vacuum in said apertures and groove, and a second disc turing in the 30 reverse direction having a side and face port adapted to register with the port in the distributor head and the aperture passing from side to side through the disc to buckle the paper.
- 35 3. In a feeder, means to support sheets, and an ejecting means consisting of a disc adapted to be rotated in one direction and having a plurality of apertures passing from the side of the disc to the face of the disc and a groove in the side of the disc, an aperture passing through the disc from one side to the other, a distributor head having a port connected to a vacuum pump adapted to create a vacuum in said apertures and groove, a second disc turing in the reverse 45 direction having a side and face port adapted to register with the port in the distributor head and the aperture passing from side to side through the disc to buckle the paper, and means mounted on a shaft operating the disc for operating the second disc in the reverse direction.
- 50 4. In a feeder, means to drive an ejector disc, an ejector disc having a port from the side to the face of the disc and a port from side to side through the disc, a distributor head having a port connected to a source of vacuum adapted to register with said ports, and a buckling disc having a port 55 through the side communicating with the
- 5 5. In a feeder, means to drive an ejector disc, an ejector disc having a port from the side to the face of the disc and a port from side to side through the disc, a distributor head having a port connected to a source of vacuum adapted to register with said ports, and a buckling disc having a port through the side communicating with the face of the buckling disc adapted to register with the port that passes from side to side through the ejector disc, and means for moving said discs in opposite directions.
- 10 6. In a feeder, means to drive an ejector disc, an ejector disc having a port from the side to the face of the disc and a port from side to side through the disc, a distributor head connected to the source of vacuum adapted to register with said ports, and a buckling disc having a port through the side communicating with the face of the buckling disc adapted to register with the port that passes from side to side through the ejector disc, means for moving said discs in opposite directions, said means consisting of a shaft for supporting and driving the ejector disc which is relatively larger than the buckling disc and means carried on said shaft for engaging with the buckling disc and means to support said buckling disc against the face of the ejecting disc.
- 15 7. In a feeder, means to drive an ejector disc, an ejector disc having a port from the side to the face of the disc and a port from side to side through the disc, a distributor head connected to the source of vacuum adapted to register with said ports, and a buckling disc having a port through the side 110 communicating with the face of the buckling disc adapted to register with the port that passes from side to side through the ejector disc, means for moving said discs in opposite directions, said means consisting of a shaft for supporting and driving the ejector disc which is relatively larger than the buckling disc, means carried on said shaft for engaging with the buckling disc, means to support said buckling disc against the face of the ejecting disc, and means to maintain said distributor head against the other face of said ejector disc.
- 20 8. In a feeder, means to drive an ejector disc, an ejector disc having a port from the side to the face of the disc and a port from side to side through the disc, a distributor head connected to the source of vacuum adapted to register with said ports, and a buckling disc having a port through the side 115 communicating with the face of the buckling disc adapted to register with the port that passes from side to side through the ejector disc, means for moving said discs in opposite directions, said means consisting of a shaft for supporting and driving the ejector disc which is relatively larger than the buckling disc, means carried on said shaft for engaging with the buckling disc, means to support said buckling disc against the face of the ejecting disc, and means to maintain said distributor head against the other face of said ejector disc.
- 25 9. In a feeder, means to drive an ejector disc, an ejector disc having a port from the side to the face of the disc and a port from side to side through the disc, a distributor head connected to the source of vacuum adapted to register with said ports, and a buckling disc having a port through the side 120 communicating with the face of the buckling disc adapted to register with the port that passes from side to side through the ejector disc, means for moving said discs in opposite directions, said means consisting of a shaft for supporting and driving the ejector disc which is relatively larger than the buckling disc, means carried on said shaft for engaging with the buckling disc, means to support said buckling disc against the face of the ejecting disc, and means to maintain said distributor head against the other face of said ejector disc.
- 30 10. In a feeder, means to drive an ejector disc, an ejector disc having a port from the side to the face of the disc and a port from side to side through the disc, a distributor head connected to the source of vacuum adapted to register with said ports, and a buckling disc having a port through the side 125 communicating with the face of the buckling disc adapted to register with the port that passes from side to side through the ejector disc, means for moving said discs in opposite directions, said means consisting of a shaft for supporting and driving the ejector disc which is relatively larger than the buckling disc, means carried on said shaft for engaging with the buckling disc, means to support said buckling disc against the face of the ejecting disc, and means to maintain said distributor head against the other face of said ejector disc, and a plate having an aperture through which said discs project, the paper sheets being beneath said plate.

8. In a feeder, means to create a vacuum, means to exhaust the air from the vacuum creating means and direct such air against the pile edge to flutter the sheets in the feeder, means to support the sheets in the feeder, means to automatically maintain said sheets in the feeder at a predetermined level, pneumatic means to buckle said sheets in one direction and pneumatic separate means to 5 eject the sheets in the other direction.
9. In a feeder, means to create a vacuum, means to exhaust the air from the vacuum creating means and direct such air against the pile edge to flutter the sheets in the feeder, means to support the sheets in the feeder, means to automatically maintain said sheets in the feeder at a predetermined level, pneumatic means to buckle said sheets in one direction, pneumatic separate means to eject 15 the sheets in the other direction, and a common means for driving said buckling and ejecting means in opposite directions.
10. In a feeder, means to create a vacuum, means to discharge air into adjacent sheets to flutter them, means to support sheets adjacent an ejecting means, an ejecting means having ports for engaging with the paper to eject it, a port for transmitting the vacuum to a buckling disc and a port for the vacuum means during the inoperative ejecting period, a distributor head adjacent said ejecting disc having a port adapted to register with the ports in the disc, a buckling disc on the other side of the ejecting disc moving in the opposite direction having a port to register with one of the ports in the side of the ejecting disc, and a port on its face to pick up the paper to buckle it, and means to limit the upward movement of the paper, said discs being adapted to project through said 25 means.

In testimony whereof, I affix my signature.

ROBERT J. WATERWORTH.
